Primary Examiner — Kevin K. Rudzinski*Assistant Examiner* — Kimberly Barnes(74) *Attorney, Agent, or Firm* — Wayne & Ken, LLC;
Tony Hom(57) **CLAIM**

The ornamental design for U-shaped pillow, as shown and described.

DESCRIPTION

FIG. 1 is a perspective view of a U-shaped pillow showing my new design;

FIG. 2 is another perspective view thereof;

FIG. 3 is a front elevation view thereof;

FIG. 4 is a back elevation view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings depict portions of the U-shaped pillow that form no part of the claimed design.

1 Claim, 8 Drawing Sheets(56)
